(57) **CLAIM**

The ornamental design for a railcar follower, as shown and described.

DESCRIPTION

FIG. 1 is a top side perspective view of one form of a railcar follower showing our new design;

FIG. 2 is a front elevational view thereof;

FIG. 3 is a sectional view thereof taken along line 3-3 of FIG. 2;

FIG. 4 is top plan view thereof; with the bottom plan view being a mirror image thereof;

FIG. 5 is a rear elevational view thereof;

FIG. 6 is a right side elevational view thereof, with the left side elevational view being a mirror image thereof;

FIG. 7 is a top side perspective view of another form of a railcar follower showing our new design;

FIG. 8 is a front elevational view thereof;

FIG. 9 is a sectional view taken along line 9-9 of FIG. 8;

FIG. 10 is top plan view thereof; with the bottom plan view being a mirror image thereof;

FIG. 11 is a rear elevational view thereof; and,

FIG. 12 is a right side elevational view thereof; with the left side elevational view being a mirror image thereof.
